US0D1102693S

(12) **United States Design Patent** (10) **Patent No.:** **US D1,102,693 S**
(45) **Date of Patent:** **** Nov. 18, 2025**

(54) **USER INTERFACE**

(71) Applicant: **SHARKNINJA OPERATING LLC**,
Needham, MA (US)

(72) Inventors: **Steven Gacin**, Pawtucket, RI (US);
Casey McClay, Medford, MA (US);
Kevin Kelemen, Randolph, MA (US);
Owen R. Johnson, Needham, MA
(US); **Street Barnett**, Watertown, MA
(US); **Patrick Cleary**, Allston, MA
(US); **Vignesh Chari**, Henrietta, NY
(US); **Alex Moschella**, Norton, MA
(US)

(73) Assignee: **SharkNinja Operating LLC**,
Needham, MA (US)

(**) Term: **15 Years**

(21) Appl. No.: **29/934,279**

(22) Filed: **Mar. 25, 2024**

Related U.S. Application Data

(62) Division of application No. 29/787,216, filed on Jun.
4, 2021, now Pat. No. Des. 1,035,194.

(57) **CLAIM**

The ornamental design for a user interface, as shown and described.

DESCRIPTION

FIG. 1 is a front view of a user interface of FIG. 1;
FIG. 2 is a rear view of the user interface of FIG. 1;
FIG. 3 is a top view of the user interface of FIG. 1;
FIG. 4 is a bottom view of the user interface of FIG. 1;
FIG. 5 is a left view of the user interface of FIG. 1;
FIG. 6 is a right view of the user interface of FIG. 1;
FIG. 7 is a perspective front, top, right of the user interface of FIG. 1;
FIG. 8 is a perspective front, top, left of the user interface of FIG. 1;
FIG. 9 is a perspective rear, top, right of the user interface of FIG. 1;
FIG. 10 is a perspective rear, top, left of the user interface of FIG. 1;
FIG. 11 is a perspective front, bottom, right of the user interface of FIG. 1;
FIG. 12 is a perspective front, bottom, left of the user interface of FIG. 1;
FIG. 13 is a perspective rear, bottom, right of the user interface of FIG. 1; and

(Continued)

FIG. 14 is a perspective rear, bottom, left of the user interface of FIG. 1;
 FIG. 15 is a plan view of a two-dimensional user interface;
 FIG. 16 is a front perspective view of the user interface of FIG. 15;
 FIG. 17 is a front right perspective view of the user interface of FIG. 15;
 FIG. 18 is a front left perspective view of the user interface of FIG. 15;
 FIG. 19 is a rear left perspective view of the front of FIG. 15; and,
 FIG. 20 is a rear right perspective view of the front of FIG. 15.
 The broken lines in the drawings depict unclaimed subject matter that forms no part of the claimed design.

1 Claim, 16 Drawing Sheets
